UNITED STATES PATENT OFFICE.

DAVID FREDERIC WEYL, OF NEW YORK, N. Y.

DESIGN FOR A TRIMMING.

40,589.

Specification for Design. Patented Mar. 22, 1910.

Application filed January 19, 1910. Serial No. 538,957. Term of patent 3½ years.

To all whom it may concern:

Be it known that I, DAVID F. WEYL, a citizen of the United States, residing in the city of New York, borough of Manhattan, in the county and State of New York, have invented a new, original, and ornamental Design for Trimmings, of which the following is a specification, reference being had to the accompanying drawing, forming a part thereof.

The figure is a plan view of a strip of trimming showing my new design.

I claim:

The ornamental design for a trimming, as shown.

DAVID FREDERIC WEYL.
